UNITED STATES PATENT OFFICE

GEORGE ALFRED ALLEN, OF MONTEBELLO, CALIFORNIA

SPRINKLER

Application filed April 16, 1930. Serial No. 444,772.

This invention relates to a sprinkler particularly applicable to large commercial installations such as orchards, vineyards, truck gardens, and the like.

5 An object of my invention is to provide a sprinkler which will effectively cover a large area with a uniform layer of water extending from the sprinkler itself to the extreme edge of the circle.

10 Another object is to provide a sprinkler which is rotated by the stream of water passing therethrough, said stream passing out of two oppositely disposed nozzles.

15 Still another object is to provide an effective means of breaking up the stream of water passing out of one of the nozzles, so that it is distributed in a uniform manner close to the sprinkler itself.

20 A further object is to provide a novel bearing upon which the sprinkler rotates, said bearing including a novel means of preventing the accumulation of sand therein.

25 Other objects, advantages and features of invention may appear from the accompanying drawings, the subjoined detailed description and the appended claims.

In the drawings

Figure 1 is a side elevation of my sprinkler.

30 Figure 2 is a side elevation of the dispersion element.

Figure 3 is a fragmentary, longitudinal, sectional view of one of the nozzles.

Figure 4 is a sectional view taken on line 4-4 Figure 3.

35 Figure 5 is a fragmentary, longitudinal sectional view of the sprinkler body.

Referring more particularly to the drawings, the numeral 1 indicates a stand-pipe 40 upon which my sprinkler is mounted. A coupling 2 screws on to the top of the stand-pipe. A journal pipe 3 screws into the coupling 2 and extends into the sprinkler. A bearing cup 4 is journaled on the pipe 3 and the cup includes a depending sleeve 5 which closely surrounds the pipe 3. The bottom of

the sleeve 5 is spaced above the coupling 2 so that longitudinal movement of the cup 4 and its attached parts is permitted.

50 A head 6 is provided on the top of the pipe 3, and a tapered seat 7 is formed below the head 6. An annular ring 8 is integrally formed on the cup 4, and the sharp upper edge of this ring bears against the seat 7. The ring 8 prevents sand from accumulating on the seat 7, and also in the sleeve 5 and the sharp upper edge of the ring also forms an effective thrust bearing with a minimum of bearing surface.

55 The sprinkler body 9 screws into the cup 4 and the body is open at the bottom and closed at the top. A nozzle pipe 10 screws into one side of the body 9 and a second nozzle pipe 11 screws into the other side of the body. These two pipes are oppositely disposed and extend upwardly at an angle. The pipe 10 is longer than the pipe 11, the purpose of which will be further described.

60 A nozzle tip 12 screws on to the outer end of the pipe 10 and this tip is provided with an eccentric bore 13. The eccentric bore creates a horizontal force on the end of the pipe which rotates the body 9. The pipe 10 is made quite long so as to utilize to the fullest the somewhat smaller force 65 exerted by the water in its passage through the eccentric bore. The water passes directly from the tip 12 and is thrown to a considerable distance and covers the outer area which is to be watered.

70 A nozzle tip 14 screws on to the end of the pipe 11 and a dispersion element 15 is also secured to the pipe 11. The dispersion element includes a ring 16 which encircles the pipe and is adjustable thereon. A set screw 17 holds the dispersion element in 75 position and against movement. An arm 18 projects outwardly from the ring 16 and a plate 19 is rotatably mounted on the outer end of the arm 18. On the plate 19, I provide a plurality of upstanding dispersion 80

vanes consisting of one long vane 20 which passes through the stream of water projecting from the tip 14 and breaks up this stream so that the water is thrown closely about the sprinkler. A driving vane 21 is placed at right angles to the stream of water from the nozzle 14 when the vane 20 is just entering that stream, thus forcing the vane through the stream to effectively break up 5 said stream. A rotating vane 22 extends in an opposite direction from the vane 21, and serves to throw the plate 19 around so that the larger vane 20 is again brought into position as shown in Figure 1. The reactance of the plate and the vanes thereon also 10 creates a rotating force.

Normally when water is not flowing through the stand-pipe 1, the body and the cup 4 drop down along the pipe 3 and 15 rest on the top of the coupling 2. As soon as water enters the stand-pipe it strikes against the top of the body 9 and forces the body upwardly along the pipe 3 until the position shown in Figure 5 is reached.

20 25 As long as water passes into the sprinkler, the cup 4 and the body 9 will be in raised position and will bear against the head 6 and the seat 7. By this arrangement a very light running, freely turning sprinkler is 30 provided which requires very little rotative force to actuate the same. The dispersion element 15 breaks up the stream of water which is emitted from the pipe 11 and distributes it evenly in the area close to the 35 sprinkler. The water from the pipe 10 and nozzle tip 12 covers the outer areas.

Having described my invention, I claim:

1. A sprinkler comprising a stand-pipe, a body, a cup into which said body is screwed, 40 a journal pipe extending through the cup into the body, a pair of diverging pipes extending from the body, a nozzle tip on one of the pipes, said nozzle tip having an eccentric bore therein, a nozzle tip on the second pipe, a dispersion element, a ring on the dispersion element encircling the second pipe, means adjustably securing the ring to the second pipe, an arm extending from the ring, a plate rotatably mounted on the arm in front 45 of the second nozzle, and a plurality of vanes on said plate extending into the path of the stream of water from the second nozzle.
2. A sprinkler comprising a stand-pipe, a coupling screwed to the top of the stand-pipe, 50 a body, a cup into which the body is screwed, a journal pipe rising from the coupling through the cup into the body, a head on the top of the journal pipe, said cup being 55 slidably on the journal pipe, an annular ring rising from the cup and adapted to bear against the head, a pair of diverging pipes 60 extending from the body, one of said pipes being longer than the other, a nozzle tip on the longer pipe, said nozzle tip having an eccentric bore therethrough, a nozzle tip 65

on the shorter pipe, a dispersion element including a ring, means adjustably securing the ring to the shorter pipe, an arm projecting from the ring, a plate rotatably mounted on the arm, said plate being positioned in front of the nozzle on the shorter arm, a long dispersing vane on the plate and a pair of shorter vanes on the plate, said shorter vanes being substantially at 70 right angles to the longer vane. 75

In testimony whereof, I affix my signature.

GEORGE ALFRED ALLEN.
